UNITED STATES PATENT OFFICE.

ABRAHAM M. SMOLENS, OF BROOKLYN, NEW YORK.

DESIGN FOR A FIGURE WHEELED TOY.

Application filed November 27, 1926. Serial No. 19,860. Term of patent 7 years.

To all whom it may concern:

Be it known that I, ABRAHAM M. SMOLENS, a citizen of the United States of America, residing at Brooklyn, Kings County, State of New York, have invented a new, original, and ornamental Design for a Figure Wheeled Toy, of which the following is a specification, reference being had to the accompanying drawing, forming part hereof, in which—

Fig. 1 illustrates a side elevation of a figure wheeled toy showing my new design, and Fig. 2 is an end view thereof.

I claim:

The ornamental design for a figure wheeled toy, as shown.

Signed at New York city, N. Y., this 24th day of November, 1926.

ABRAHAM M. SMOLENS.
